Victor G. Evans
ATTORNEY

UNITED STATES PATENT OFFICE.

ROYAL BARLOW NICHOLS, OF EAST LYNN, MASSACHUSETTS.

SWIMMING BOARD.

1,402,529.

Specification of Letters Patent. Patented Jan. 3, 1922.

Application filed April 5, 1921. Serial No. 458,714.

To all whom it may concern:

Be it known that I, ROYAL B. NICHOLS, a citizen of the United States, residing at East Lynn, in the county of Lynn and State 5 of Massachusetts, have invented new and useful Improvements in Swimming Boards, of which the following is a specification.

This invention relates to a buoyant device for facilitating swimming, the general 10 object of the invention being to construct a body of buoyant material and so formed that a person can support himself thereon while in the water so that he can teach himself to swim or a swimmer can use the 15 same to rest himself.

Another object of the invention is to shape the body so that it can be shoved through the water with the least possible resistance to its passage by the water.

20 This invention also consists in certain other features of construction and in the combination and arrangement of the several parts, to be hereinafter fully described, illustrated in the accompanying drawings 25 and specifically pointed out in the appended claim.

In describing my invention in detail, reference will be had to the accompanying drawings wherein like characters denote like 30 or corresponding parts throughout the several views, and in which:—

Figure 1 is a plan view of a body constructed in accordance with my invention.

Figure 2 is an edge view with parts 35 broken away to show the construction.

As shown in these views the device is formed of a frame 1 and a filling 2 of cork or other buoyant material. The body is formed with flat upper and lower surfaces

with its edges of substantially elliptical 40 form to provide pointed ends so that the water will offer but little resistance to the passage of the body therethrough. The ends may be tipped with metal, as shown at 3, and the cork is covered by canvas or the 45 like, as shown at 4. In order to strengthen the device I place a cross piece 5 at the center of the body which has its ends secured to the frame, the frame being also suitably secured to the cork filling. 50

This device is made large enough to support a person in the water so that he can teach himself to swim or a swimmer can use the device to support himself at the surface of the water. 55

It is thought from the foregoing description that the advantages and novel features of my invention will be readily apparent.

I desire it to be understood that I may make changes in the construction and in 60 the combination and arrangement of the several parts, provided that such changes fall within the scope of the appended claim. 65

What I claim is:—

A device of the class described comprising a frame of substantially elliptical shape and a filling of buoyant material, the ends being tipped with metal and a canvas covering the cork, a cross piece provided at 70 the center of the body and having its ends secured to the frame and the frame being suitably secured to the cork filling, said body having its ends pointed so that the water will offer little resistance to the passage of 75 the body therethrough.

In testimony whereof I affix my signature.

ROYAL BARLOW NICHOLS.
